(57) **CLAIM**

The ornamental design for an origami paper airplane, as shown and described.

DESCRIPTION

FIG. 1 is a front plan view showing my new design in its pre-folded state as a flat patterned sheet of paper, the reverse side being unornamented;

FIG. 2 is a right and rear perspective view of the design in its assembled state; and,

FIG. 3 is a left and front perspective view of the design in its assembled state.

1 Claim, 3 Drawing Sheets

FIG. 1

FIG. 2

FIG. 3
